UNITED STATES PATENT OFFICE.

JOHN J. MATLEVISH, OF CHRISTOPHER, ILLINOIS.

CHIMNEY CAP.

Application filed January 14, 1928. Serial No. 246,771.

This invention relates to chimney caps or cowls, and has for its primary object to provide a comparatively simple and inexpensive device of this character adapted to form a partial closure for the top of the chimney, and thereby prevent wind, rain, snow and other foreign matter from passing down the chimney.

A further object is to provide an improved hood for the cap, and simple and efficient mounting means for the hood, whereby the latter may be readily removed for renewal or repair.

A still further object is to provide a chimney cap embodying a minimum number of metallic parts capable of corroding or deteriorating from long exposure to the elements, and including a molded concrete supporting base for the hood adapted to be secured by mortar on the top of the chimney proper to form a finishing block for the latter.

Another object is to provide the supporting base with removable hood supporting posts or upright rods, so that the latter may be firmly attached, although readily detachable for renewal.

Still another object is to generally improve this class of devices so as to increase their utility, durability and efficiency, as well as to minimize the cost of manufacture.

The invention consists in the novel form, combination and arrangement of parts hereinafter more fully described, shown in the accompanying drawings and claimed.

In the drawings:

Figure 1 is an elevational view of a chimney cap constructed in accordance with the present invention and mounted on the top of a chimney.

Figure 2 is a top plan view thereof, partly broken away and in section.

Figure 3 is a vertical section on line 3—3 of Figure 1.

Figure 4 is a view similar to Figure 3, showing a modification of the invention.

Figure 5 is a horizontal section showing a further modification, and

Figure 6 is a fragmentary transverse vertical section on line 6—6 of Figure 5.

Referring more in detail to the drawings, the invention is illustrated in connection with a chimney proper 5 of ordinary brick construction, and includes a supporting base 6 consisting of a hollow molded concrete block adapted to be secured by mortar on top of the chimney proper to form a finishing block for

the latter. This base block 6 is of slightly larger size at the bottom than the upper end of the chimney so as to overhang the sides of the latter, the sides of the block all inclining or sloping outwardly and downwardly to shed rain and the like outwardly of the sides of the upper end of the chimney and preserve the adjacent bricks and mortar from moisture.

The central vertical passage or opening 7 in the base block is registered with and forms a continuation of the smoke passage or flue of the chimney, and completely embedded in the base block at the four corners of the latter are nuts or nut members 8 into which are removably threaded the lower ends of hood supporting posts or upright rods 9.

The lower ends of the rods 9 are removably fitted in vertical openings formed in the base block 6 in alinement with and above the threaded bores of the nut members 8, so that the lower terminals of said rods may be engaged with or disengaged from the base block as well as the nut members for ready renewal.

A hood or hood plate 10 is removably mounted on the upper ends of the posts or rods 9 so as to be supported in spaced relation to and above the base block 6 to permit the escape of the smoke and products of combustion, while preventing down-drafts and entrance of rain, snow and the like directly downward into the chimney. The removability of the hood permits of its ready renewal, and said hood is preferably formed of an elongated rectangular sheet of metal having an upwardly arched intermediate portion 11 and inclined ends 12 to readily shed rain and the like. The hood plate is a greater area than that of the base block so as to project outwardly of the sides of the latter and effectively exclude the rain and the like from the interior of the chimney and shed the same outwardly of the sides of the latter.

The upper ends of the posts 9 pass through openings in the hood plate 10 at the juncture of the inclined ends 12 with the arched portion 11, and in the forms of the invention shown in Figures 1 and 3 the hood is clamped between pairs of nuts 13 removably and adjustably threaded on the upper ends of the posts 9.

In the form of the invention shown in Figure 4, metallic spacing and protecting sleeves 14 are placed on the posts 9 with their lower ends resting on the top of the base block 6, while the hood is removably clamped down against the upper ends of the sleeves 14 by

nuts 15 applied to the projecting upper ends of the posts 9. In the form of the invention shown in Figure 5, the nut members 8 are integrally connected by horizontal bars 16 which aid in properly positioning the nut members and reinforce the base block. Otherwise, the forms of Figures 4 and 5 are the same as the form of Figure 1.

Minor changes may be made without departing from the spirit and scope of the invention as claimed.

What I claim as new is:

1. A chimney cap comprising a molded concrete base block having a flue passage and provided with upright corner posts, a hood mounted on the upper ends of the corner posts, said hood embodying a metallic plate having an upwardly arched intermediate portion and inclined ends and pairs of nuts 15 threaded on the upper ends of the corner posts between which the hood is removably clamped, said corner posts passing through the hood at the juncture of the inclined ends of the hood with the arched intermediate portion thereof.
2. A chimney cap of the class described comprising a precast concrete base block of

truncated pyramidal configuration having a flue passage, a metallic frame embedded centrally in said block and provided at its corners with screw-threaded holes, said concrete block having vertical bores in alignment with said screw-threaded holes, a plurality of rods screw-threaded at their opposite ends, the lower screw-threaded ends extending down through said vertical bores and being threaded into the holes in said metal frame, pairs of clamping nuts threaded on the upper ends of the rods, a substantially rectangular plate of an area greater than the area of said base, said plate being stamped to provide a transversely extending upwardly and longitudinally bowed central portion and down-bent end portions, the portions of the plate between the down-bent ends and the longitudinally bowed central portion being provided with openings through which the upper screw-threaded ends of said rods project, said clamping nuts engaging opposite sides of said plate and securing the latter on the upper ends of the rods.

In testimony whereof I affix my signature.

JOHN J. MATLEVISH.
